UNITED STATES PATENT OFFICE.

LEO I. KELLY, OF DETROIT, MICHIGAN.

GENERATING PLANT.

1,283,797.

Specification of Letters Patent.

Patented Nov. 5, 1918.

Application filed October 22, 1917. Serial No. 197,845.

To all whom it may concern:

Be it known that I, LEO I. KELLY, a citizen of the United States, residing at Detroit, county of Wayne, State of Michigan, have invented a certain new and useful Improvement in Generating Plants, and declare the following to be a full, clear, and exact description of the same, such as will enable others skilled in the art to which it pertains to make and use the same, reference being had to the accompanying drawings, which form a part of this specification.

My invention relates to a steam generating plant for automobiles and objects of my improvements are to cheapen the construction of the generator, to facilitate assembling and disassembling and to secure certain advantages in the operation of the same hereinafter indicated.

20 In the drawings:

Figure 1 is a plan view partly in section of a generator embodying my invention.

Fig. 2 is an elevation of a portion of said generator.

25 Fig. 3 is a detail showing a part of the apparatus shown in Fig. 2.

Fig. 4 is a sectional detail showing the mode of connecting the parts shown most distinctly in Fig. 3.

30 Fig. 5 is a sectional view of the arrangement in the delivery passages for steam.

As shown in Fig. 1 there is a casing *a* in which is inclosed a steam generating apparatus divided into two parts *h* and *h*², each of the parts is capable of generating steam for power by itself and both deliver the steam, through the pipes *g* *g* and *g*² *g*², respectively, into the casing *k* of a throttle valve by which the rate of delivery of steam to the motor is controlled through the valves *i* operated by the stem *j*.

One part *h* of the generating plant communicates by pipes *g* *g* with the casing *k* upon one side of said casing and the part *h*² communicates with said casing upon the other side by the delivery pipes *g*² *g*². *g*³ *g*³ are check valves in the pipes *g*² *g*² opening toward the casing *k*. *g*⁴ *g*⁴ are check valves in the delivery pipes *g* *g* opening toward the casing *k*.

50 *b* is a preheating apparatus to which the feed water passes through the pipe *f*, and from which it passes, through the delivery pipe *c* into the generator section *h*², and through the pipe *c*² into the generator section *h*. The preheating apparatus *b* is enclosed in a separate casing *a*² which is re-

movably secured in an opening in the side of the casing *a*. The preheater is made up of a series of tubes communicating with a delivery manifold *b*² which manifold is connected by unions *b*³ *b*³ with the pipes *c* and *c*². *b*⁴ *b*⁴ are check valves in the delivery passage from the economizer or preheater *b* to the generator sections opening toward said sections and of course closing in the opposite direction. *d* *d* are cocks adapted to close the passage between the economizer *b* and the generator sections *h* *h*². *e* is a pet cock in the passage *c* on the generator side of the cock *d*.

By loosening the union *b*³ the economizer *b* with its casing *a*² may be removed as a unit and conveniently replaced by reversing the operation.

75 If a tube in one of the generator sections *h* and *h*² becomes broken, or the section wall becomes ruptured in any way, the check valves *g*³, *g*⁴ or *b*⁴ will automatically shut off that section from communication with the other section and by trial of the pet cock *e* the operator can ascertain which section has become broken and close the cock *d* communicating with said section.

The constituent parts of the generator 85 each consists of an upper and lower manifold *m*² *m*³ (Fig. 3) and these manifolds are joined together by tubes or passages constructed as follows: A pipe *m*⁴ is bent into a series of parallel portions joined 90 by curves or loops and this coil is of a breadth proportioned to the length of the manifolds *m*² *m*³ and is united thereto as a unit in the following manner: The loops of the coil of the pipe *m*⁴ intermediate its 95 ends are cut away as shown at *m*⁵ and a corresponding aperture is made in the manifold so that these loops are placed so that the apertures register with the apertures of the manifolds and the walls surrounding 100 the aperture in the loop engages the wall around the apertures of the manifold. These walls are then united by welding or brazing as the case may be.

The ends of the pipe *m*⁴ are preferably 105 contracted as shown at *m*⁶ and pass into an aperture, the outer walls engaging the inner walls of said aperture as shown in Figs. 3 and 4. This forms a very cheap construction and one easy to assemble and cheap to 110 replace.

What I claim is:

1. In a generator, two manifolds, a pipe bent into a plurality of loops with approxi-

mately parallel portions, said loops being provided with openings at their bent portions, said manifolds being provided with openings, the openings in said loops registering with the openings in said manifolds and the walls surrounding said openings being united for the purpose described.

2. In a generator, two manifolds, a pipe bent into a loop with approximately parallel portions in a plane passing through the axes of said manifolds, said loop being provided with openings at the bent portions, said manifolds being provided with openings, the openings in said loop registering with the openings in said manifolds and the walls surrounding said openings being united for the purpose described.

3. A structure for generators consisting in a manifold, a pipe having curved and approximately parallel portions in a plane 20 passing through the axis of said manifold,

said manifold being provided with apertures through its walls, said pipe being provided with apertures in the curved portions, the apertures in said pipe and said manifold 25 registering and having their walls united for the purpose described.

4. A structure for generators consisting in a manifold, a pipe having curved and approximately parallel portions in a plane 30 passing through the axis of said manifold, said manifold being provided with apertures through its walls, said pipe being provided with apertures in the curved portions, the apertures in said pipe and said manifold 35 registering and having their walls united, an end of said pipe passing through an aperture in said manifold and being secured therein.

In testimony whereof I sign this specification.

LEO I. KELLY.
